CLAIM

The ornamental design for a glass breaker, as shown and described.

DESCRIPTION

FIG. 1 is a left side elevation view of the glass breaker embodying the new design installed on a pocket knife; FIG. 2 is a top perspective view of the glass breaker; FIG. 3 is a left side elevation view of the glass breaker, with the right side elevation view being identical; FIG. 4 is a top plan view of the glass breaker, with the bottom plan view being identical; FIG. 5 is a rear side elevation view of the glass breaker; and, FIG. 6 is a front side elevation view of the glass breaker. The broken lines in the drawings represent portions of the glass breaker that form no part of the claimed design.
